IRVING B. CRANDALL, OF NEW YORK, N. Y., ASSIGNEE TO WESTERN ELECTRIC COMPANY, INCORPORATED, OF NEW YORK, N. Y., A CORPORATION OF NEW YORK

DAMPING MATERIAL FOR TELEPHONES

1,255,861.

Specification of Letters Patent. Patented Feb. 12, 1918.

Application filed August 14, 1916. Serial No. 114,795.

To all whom it may concern:

Be it known that I, IRVING B. CRANDALL, a citizen of the United States, residing at New York, in the county of New York and State of New York, have invented certain new and useful Improvements in Damping Material for Telephones, of which the following is a full, clear, concise, and exact description.

10 This invention relates to sound absorbing materials and to the damping of vibrating members, and in particular to vibrating diaphragms such as are used in telephonic communication in phonographs, etc. Its object is to so damp the vibrations of such diaphragms as to suppress the tendency of these diaphragms to vibrate with certain frequencies.

15 In telephone practice, it has been found that diaphragms, both for receivers and transmitters, have a more or less marked natural period and this is usually in the neighborhood of 900 cycles per second. This characteristic of diaphragms to respond 20 more strongly to oscillations of a certain period causes a distortion of the sound impulses impressed on them and thereby causes a decrease in the quality of the transmitted speech. The invention, then, has for its purpose 25 primarily to make improvements in the quality of speech as transmitted by previous telephonic or phonographic apparatus, and accomplishes this purpose by decreasing the tendency of the vibrating parts to respond 30 to certain frequencies.

35 The invention will be better understood by reference to the following specification and accompanying drawing, in which Figure 1 shows curves indicating the degree of resonance which may be present in diaphragms with different degrees of damping. Figs. 2 and 3 show forms of a telephone transmitter and receiver embodying this invention.

40 Referring to Fig. 1, it will be seen that frequencies are indicated as abscissae and the degree of response of a vibrating diaphragm by the ordinates. Curve A gives the resonance curve for a diaphragm which is rather sharply responsive or sharply tuned to a 45 certain frequency—such, for example, as 900 cycles per second. Such a diaphragm would be very undesirable for reproduction of speech because of the enormous emphasis with which notes or vibrations of a certain

55 pitch or frequency would be brought out to the relative detriment of other frequencies. Such diaphragms, furthermore, could be obtained only with some difficulty and by special provision. In general, telephone diaphragms do not have such a marked resonance as indicated by this curve, but their 60 resonance characteristic would be indicated more correctly by curve B because of various frictional forces. Even with such a diaphragm, however, it would be noted that 65 over a certain limited range of frequencies the response is much greater than for other regions, and speech transmitted by such diaphragms shows a considerable amount of distortion and corresponding decrease in the 70 quality of transmission. The ideal diaphragm should have a resonance curve represented by a line which is parallel to the horizontal axis, indicating an equal response to all frequencies. It is, however, impossible 75 to obtain such a diaphragm, but with this invention, it is possible to cause a diaphragm to vibrate with a characteristic such as shown in curve C, which is a close approximation to the ideal condition. 80

A change from the curve B to the curve C may be obtained by increasing the damping factor of the diaphragm. In general, the damping factor of any vibrating system depends only upon the frictional forces and 85 upon the inertia, being proportional to the frictional forces and inversely proportional to the inertia or mass of the system. A diaphragm having a resonance characteristic such as given by B could therefore be 90 changed to approach the resonance characteristic C by decreasing the inertia or mass of the diaphragm or by increasing the frictional forces. Attempts have been made to obtain a flatter characteristic by changing 95 both the frictional forces and the inertia, but it has been found that a limit is soon reached in the matter of decreasing the mass. Various attempts have been made to increase the frictional forces by the use of damping 100 springs or strips or rings of felt or other padding material, all of which have been attended with a certain measure of success. It has been found, however, that rings of felt and similar material possess a certain 105 amount of elasticity themselves and as such are not ideal damping materials.

It has been found that very smooth, finely

divided, non-packing metallic powders, of such metal as copper, magnesium, aluminum and so forth, but in particular aluminum and magnesium powder, posses an exceedingly small amount of elasticity, and, taken in mass, submit to distorting or displacing forces very readily with a remarkably small tendency to return to their former position. This invention consists, then, in the above discovery and in its application to the damping or vibrating members. One manner of its application is indicated in Fig. 2, in which 10 represents a suitable diaphragm of the usual type used in telephony. 11 15 represents a shell or case supporting and containing the usual electromagnet 12 for receiving or generating telephonic currents. As such, this device constitutes a well-known form of telephone receiver or transmitter. 20 Within this shell or container, and completely filling the same so as to be in intimate contact with the shell and with the diaphragm 10, is placed finely divided or powdered aluminum or magnesium 13, and 25 it is found as a result that the diaphragm 10 is enormously damped and responds almost equally to all vibrations impressed thereupon, the resonance curve being similar to that shown at C in Fig. 1. While I have 30 in particular mentioned aluminum and magnesium, I find of the two that aluminum is preferable in that it has both a very low mass and a very low elasticity.

Fig. 3 shows a similar application of this invention to a well-known form of microphone transmitter and it is apparent from the description of Figs. 2 and 3 that use may be made of such a damping material in practically all telephone transmitters and 40 receivers with only minor changes in the construction to prevent short-circuiting and to maintain the metallic powder in contact with the vibrating member.

In the usual telephone transmitter or receiver it is found that the damping coefficient is of the order of 150. In the instruments which are damped, as shown in Figs. 2 and 3, the damping coefficient is about ten times this value.

While this invention has been shown applied in particular to a telephone transmitter or receiver, it is to be understood that it may be equally well applied in numerous other forms of apparatus—such, for example, as phonograph diaphragms and other places in which it is desired, for one reason or another, to have large damping for vibrating parts.

This damping material may also be used 60 in making sound-proof cavities or spaces, being used, for example, as a filler between two walls surrounding said cavity or space.

Having now described this invention,

what I claim to be new and desire to secure by Letters Patent is:

65

1. A device for converting mechanical vibrations and electrical impulses comprising a mechanically vibrating member, an electrical translating device associated therewith, and independent means for damping the vibration of said member, said independent means consisting of a finely divided metal.

2. A device for converting mechanical vibrations and electrical impulses comprising a mechanically vibrating member, an electrical translating device associated therewith, and independent means for damping the vibration of said member, said independent means consisting of a finely divided mass of aluminum or magnesium.

3. A device for converting mechanical vibrations and electrical impulses comprising a mechanically vibrating diaphragm, an electrical translating device operatively associated with a portion of one surface of said diaphragm, and independent means for damping the vibration of said diaphragm, said means consisting of a finely divided metal in contact with substantially all of the remaining vibratory portions of said surface not associated with said electrical translating device.

4. In apparatus comprising vibrating members, means for transmitting the vibration of said members, and independent means for damping the vibration of said members, said independent means consisting of a finely divided metal.

5. In apparatus comprising vibrating members, means for transmitting the vibrations of said members, and independent means for damping the vibrations of said members, said independent means consisting of a finely divided mass of aluminum or magnesium.

6. In apparatus comprising a vibrating diaphragm, means operatively associated with a portion of one surface of said diaphragm for transmitting the vibrations of said diaphragm, and independent means for damping the vibrations of said diaphragm, said independent means consisting of finely divided metal in contact with substantially all remaining vibrating portions of said surface not associated with said vibration transmitting means.

7. A telephone instrument comprising a vibrating diaphragm, a variable resistance device operatively associated with a portion of one surface of said diaphragm, and a damping material for said diaphragm independent of said variable resistance device, said material consisting of a finely divided metal associated with substantially all remaining vibrating portions of said surface

125

not associated with said variable resistance device.

8. A telephone instrument comprising a vibrating diaphragm, a variable resistance device operatively associated with a portion of one surface of said diaphragm, and a damping material for said diaphragm independent of said variable resistance device, said material consisting of finely divided

aluminum or magnesium associated with substantially all remaining vibrating portions of said surface not associated with said variable resistance device.

In witness whereof, I hereunto subscribe my name this 12th day of August, A. D., 1916.

IRVING B. CRANDALL.
